FLEXIBLE FENCE POST

John T. Fulbright, Rockford, Mich., assignor of one-half
to Everett A. Johnson, Park Ridge, Ill.

Filed May 26, 1964, Ser. No. 80,149

Term of patent 14 years

(Cl. D28—1)

FIGURE 1 is a rear elevational view of a fence post embodying my new design;

FIGURE 2 is a side elevational view of the fence post shown in FIGURE 1;

FIGURE 3 is a top view of the fence post enlarged to illustrate details thereof; and

FIGURE 4 is a perspective of the fence post shown in FIGURES 1-3.

The dominant features of my design are shown in full lines.

The post is broken away in FIGS. 1 and 2 to indicate indeterminate length. The lower portion of the post in FIG. 4 has been omitted for convenience of illustration only.

The electric fence wire and the warning ribbon, shown in broken lines in FIGURE 4, are disclosed for illustrative purposes only.

I claim:

The ornamental design for a flexible fence post, as shown and described.
